ASSIGNMENTS, TO PIETRO D'ALESSANDRO, TRUSTEE.

POWDER-DISTRIBUTING BRUSH.

1,401,508.

Specification of Letters Patent. Patented Dec. 27, 1921.

Application filed July 23, 1920. Serial No. 398,509.

To all whom it may concern:

Be it known that I, PIETRO D'ALESSANDRO, a subject of the King of Italy, and a resident of Syracuse, in the county of Onondaga and State of New York, have invented 5 a certain new and useful Powder-Distributing Brush, of which the following is a specification.

This invention relates to powder brushes, 10 such as are used by barbers and has for its object a particularly simple and efficient mechanism by means of which a predetermined amount of powder as talcum powder is delivered if desired while the brush is 15 being used, and the invention consists in the combinations and constructions herein-after set forth and claimed.

In describing this invention, reference is had to the accompanying drawings in which 20 like characters designate corresponding parts in all the views.

Figure 1 is a vertical sectional view of a brush embodying my invention.

Figs. 2 and 3 are opposite face views of 25 the partition and delivery mechanism.

Fig. 4 is a sectional view on the plane of line 4—4, Fig. 1.

This brush comprises generally, a hollow body, a brush having a head located in the 30 lower end of the hollow body, the head and body having relative turning movement and delivery mechanism located in the hollow body above the head, connections between the head and the delivery mechanism where- 35 by upon relative turning movement of the head and body the delivery mechanism is operated to deliver a predetermined amount of powder from the hollow body above such mechanism and a stop for limiting the relative turning movement of the head and 40 body.

1 designates the body which as here shown is provided with an enlarged hollow cylindrical lower portion, and an upper hollow 45 portion 2 which serves as a handle and a receptacle for the powder, the upper end of the handle being open in order that the talc powder can be supplied to the receptacle within the handle 2. The upper end of the handle 2 is closed by a closure as a plug 3 threading thereinto.

4 designates the bristles of the brush which are held in a suitable head 5 mounted in the lower end of the body 1, the head 55 being formed with an opening 6 through

which the powder is delivered in the bristles of the brush. Preferably, the lower cylindrical portion of the body 1 is internally threaded and the head 5 threads into the body, it being limited in its inward movement by a marginal flange 5^a which engages the edge of the lower end of the body 1.

The delivery mechanism comprises a perforated partition 7 located in the body above the partition and cut-off members 8 and 9 movable over the lower and upper faces of the partition and arranged at a right angle to each other whereby one member covers the adjacent end of the perforation or perforations of the partition 7 while the other member uncovers such perforation and covers other perforations. The partition 7 is here shown as formed with four delivery openings 10 arranged on a quarter or in sets 70 of two openings each arranged diametrically opposite each other. The delivery or cut-off members are here shown as wings or plates arranged to cover diametrically opposite openings 10, the wings of the lower member 8 being arranged to cover the lower ends of two of such openings 10 diametrically opposite each other while the upper member 9 is out of alignment with the same openings permitting the powder to fill into 80 such openings and cover the other two openings from which the powder has been discharged so that upon rotation of the members 8, 9 the lower member 8 uncovers such openings permitting the talcum powder to fall out while the upper member 90 covers the openings and cuts off the feed of the powder through the openings just uncovered.

During this operation, the remaining two 95 diametrically opposite openings 10 are closed at their lower ends and opened at their upper ends by the members 8, 9 permitting such openings to fill so that upon the next operation, the powder will be discharged therefrom. The delivery members 8 and 9 are mounted upon an axle 11 common to both and arranged centrally of the partition 7. The partition 7 threads into the cylindric portion of the body 1 and is 100 limited in its movement by an adjustable stop 12 as a screw threading vertically or transversely through a ring 13 which also threads into the body 1 above the partition 8.

The delivery members 8, 9 are rotated during turning of the head 5 or are held from rotation during the turning of the handle 1 relatively to the head by connections between the head 5 and the lower delivery member 8, these connections including one or more adjustable shoulders, as pins or screws 14 threading through the head from the lower side thereof and projecting into the path of shoulders 15 depending from the wings of the delivery member 8, the screws 14 being here shown as arranged diametrically opposite each other. 16 is a stop provided on the partition to limit the movement of the parts 8, 9 and hence relative rotation of the body and brush head sufficient to dislodge the head from the body. The shoulders 14 are adjustable endwise into proper relation after the brush head has been placed in the body. 20 This feature alone and together with the stops 12 and 16 holds the parts which screw thread into the body in their assembled and adjusted relation.

In operation, assuming that the handle is turned relatively to the head, the partition 7 turns with the handle and the shoulder 15 thereon engages the end of a screw 14, which holds said member 8 from rotation while the partition turns with the handle, thus uncovering the lower ends of diametrically opposite perforations 10 and closing the upper ends thereof so that the amount of powder previously located in such holes is now free to fall out through the openings 6 and into the bristles of the brush.

During this operation, the other two diametrically opposite holes 10 are closed at their lower ends and opened at their upper ends, hence upon the next operation of the brush by turning the handle in the opposite direction the last two mentioned holes will be uncovered at their lower ends and discharge the powder therein, and the first two set of holes will be uncovered at their lower ends and uncovered at their upper ends and filled for the third operation.

What I claim is:

1. A powder brush comprising a hollow body, and a brush proper having a head at one end of the hollow body, the head and body having relative turning movement, a delivery device arranged in the hollow body above the head and including a partition having perforations and cut off members movable on the upper and lower surfaces of the partition and arranged at an angle to each other whereby the lower cut-off member covers the lower end of one perforation when the upper member is out of alignment with said perforation, and covers the upper end of another perforation, means connecting the cut-off members whereby the motion of one is transmitted to the other, and connections between the head and the lower member whereby the cut-off members are operated

during relative turning movement of the head and the body, substantially as and for the purpose described.

2. A powder brush comprising a hollow body, and a brush proper comprising a head mounted in the lower end of the hollow body, a delivery mechanism comprising a partition located in the hollow body above the head, and having perforations therethrough and pivoted cut-off members mounted on the upper and lower sides of the partition and arranged at an angle to each other, said members being connected together to move as a unit, and the lower members being arranged to cover the lower end of one perforation while the upper member is out of alignment with the upper end of said perforation and covers the upper end of the other perforation, the lower member being formed with a pair of spaced shoulders, and a shoulder projecting from the head between the former shoulders whereby during rotation rotary movement of the head relatively to the body the relative position of the said members and the openings of the partition are changed, substantially as and for the purpose set forth.

3. A powder brush comprising a hollow body formed with internal threads in the lower portion thereof, a brush proper having a head threading in the body, a partition threading in the body above the head, the partition being formed with perforations therethrough, cut-off members movable on the upper and lower faces of the partition and at an angle to each other whereby the lower cut-off member covers the lower ends of the perforations while the upper cut-off member is out of alignment with the perforation, and covers the upper ends of the other perforation, the lower cut-off member being formed with depending shoulders and a pin projecting upwardly from the head into the path of the shoulders, substantially as and for the purpose described.

4. A powder brush comprising a hollow body formed with internal threads in the lower portion thereof, a brush proper having a head threading in the body, a partition threading in the body above the head, the partition being formed with perforations therethrough, cut-off members movable on the upper and lower faces of the partition and at an angle to each other whereby the lower cut-off member covers the lower ends of the perforations while the upper cut-off member is out of alignment with the perforation, means connecting the members whereby the motion of one is transmitted to the other, the lower cut-off member being formed with depending shoulders, pins projecting upwardly from the head into the path of the shoulders, and a stop located within the hollow body and coacting

with the partition to limit the inward movement thereof, substantially as and for the purpose set forth.

5. A powder brush comprising a hollow body formed with internal threads in the lower portion thereof, a brush proper having a head threading in the body, a partition threading in the body above the head, the partition being formed with perforations therethrough, cut-off members movable on the upper and lower faces of the partition and at an angle to each other whereby the lower cut-off member covers the lower ends of the perforations while the 10 upper cut-off member is out of alinement with the perforation, means connecting the members whereby the motion of one is trans-
mitted to the other, the lower cut-off member being formed with depending shoulders and pins projecting upwardly from the head 20 into the path of the shoulders, a ring threaded in the body above the partition, and a stop carried by the ring and coacting with the partition to limit the inward movement thereof, and hold it from rotating along the 25 threads during relative turning of the body and the head, substantially as and for the purpose described.

In testimony whereof, I have hereunto signed my name, at Syracuse, in the county 30 of Onondaga, and State of New York, this 29th day of June, 1920.

PIETRO D'ALESSANDRO.
